UNITED STATES PATENT OFFICE.

FREDERICK J. MARTIN, OF NEW YORK, N. Y., ASSIGNOR TO WESTERN ELECTRIC COMPANY, INCORPORATED, OF NEW YORK, N. Y., A CORPORATION OF NEW YORK.

TESTING DEVICE.

Application filed June 19, 1923. Serial No. 646,349.

To all whom it may concern:

Be it known that I, FREDERICK J. MARTIN, a citizen of the United States, residing at New York, in the county of New York, State 5 of New York, have invented certain new and useful Improvements in Testing Devices, of which the following is a full, clear, concise, and exact description.

This invention relates to testing devices 10 and more particularly to circuit testing devices.

In the installation of telephone exchanges, it is necessary that all circuits and equipment within the exchange be tested for electrical 15 defects such as "opens", "short-circuits", "reverses", etc., before the exchange is opened for public service, in order to obviate the necessity for tearing out defective circuits and apparatus after the exchange has 20 been put into use. In the manual type exchanges, incoming subscribers' lines and incoming trunks are ordinarily accessible to a plurality of operators by virtue of the fact that the lines or trunks terminate at different 25 operators' positions.

It is well known in the telephone art that incoming trunks and subscribers' lines terminate at an exchange in a plurality of separate terminals, for example the tip, ring and sleeve terminals which are electrically connected to corresponding tie or multiple wires, each tie wire interconnecting a pair of like terminals of several jacks.

It is an object of this invention to detect 30 and locate unstandard conditions in electrical circuits, and more specifically in the multiplied terminating jacks of a telephone line or trunk.

This object is accomplished in accordance 40 with the features of this invention by the provision of a testing device having two plugs adapted to interconnect as many multiplied jacks and associate them with a plurality of relays, which operate automatically 45 to successively complete electrical circuits through the tip, ring and sleeve conductors in such a manner that if any or all of these conductors are open the presence and location of such an unstandard condition is manifested in a signal.

The invention will be readily understood from the following detailed description made with reference to the accompanying drawing in which:

Fig. 1 shows a multiple jack set and the

testing circuit wherein the location of an unstandard condition is determined by the manipulation of a pair of keys or push buttons, and

Fig. 2 shows a testing circuit wherein a signal individual to each circuit being tested is provided, thereby rendering the location of an unstandard condition more readily discernible.

In Fig. 1 the tip, ring and sleeve multiple conductors 5, 6 and 7 respectively, of an incoming line are shown connected to their respective contacts of jacks 8, 9 and 10.

In testing the jack multiple for "opens", the procedure is as follows:

The plug 12 is inserted into jack 10 and plug 13 into jack 9. If the ring conductor or multiple wire 6 and the ring contacts of jacks 10 and 9 are electrically continuous, a circuit will be established for relay 14 which 75 may be traced from the negative pole of battery 15, winding of relay 14, ring contacts of plug 13 and jack 9, ring conductor 6, ring contacts of jack 10 and plug 13 to the positive pole of battery 15. Relay 14 80 energizes in this circuit and in attracting its armature establishes a circuit for relay 16. Assuming that the sleeve conductor 7 and the sleeve contacts of jacks 10 and 9 are electrically continuous, relay 16 operates in a 85 circuit which may be traced from the negative pole of battery 17, front contact and armature of relay 14, winding of relay 16, sleeve contacts of plug 13 and jack 9, sleeve conductor 7, sleeve contacts of jack 10 and 90 plug 12 to the positive pole of battery 17. Relay 16 operates in this circuit and, assuming the tip conductor 5 and the tip contacts of jacks 10 and 9 are electrically continuous,

effects the actuation of relay 18 in a circuit 95 which may be traced as follows: from the negative pole of battery 19, front contact and armature of relay 16, winding of relay 18, tip contacts of plugs 13 and jack 9, tip conductor 5, tip contacts of jack 10 and plug 12 to the positive pole of battery 19. Relay 18 in operating establishes an obvious circuit for the buzzer 20 which gives forth an audible tone. From this description it is evident that when a tester inserts the two 100 plugs 12 and 13 into two multiplied jacks and the buzzer 20 operates, he knows that the wires and contacts included between the jacks employed are respectively electrically continuous.

The failure of the buzzer 20 to operate upon the insertion of plugs 12 and 13 into two jacks such as 10 and 9 will indicate the presence of trouble in some one or all of the three circuits (tip, ring and sleeve) and the tester proceeds to locate the trouble. The key or push-button 21 is depressed whereupon the heretofore traced circuit for relay 16 is established, except that the contacts of key 21 are substituted for the contacts of ring relay 14, should said relay 16 have failed to operate when plugs 12 and 13 were inserted into jacks 10 and 9 respectively. If the sleeve circuit is electrically continuous or devoid of defects, relay 16 will operate, and as described heretofore, will establish a circuit for the tip relay 18 which in the event that the tip circuit is also intact will cause the operation of buzzer 20. Therefore, if the insertion of plugs 12 and 13 into jacks 10 and 9 respectively fails to operate the buzzer 20 and a subsequent actuation of key 21 causes the buzzer to operate, the tester knows that the "open" exists in the ring circuit.

If, after depressing the key or button 21, the buzzer fails to respond, the key 21 is released and key 22 depressed. Upon the actuation of key 22, should the buzzer respond, the tester knows that the tip circuit is intact and the trouble exists in either or both the ring and sleeve circuits.

Key 21 is then depressed, thereby completing a circuit for relay 16 independent of the contacts of relay 14. If in this case the buzzer operates, the trouble lies in the ring circuit and if the buzzer fails to operate the trouble will be found in the sleeve circuit.

From the foregoing description, it is apparent that there is more or less mental action required to determine, by the process of elimination, the exact location of the unstandard conditions. In Fig. 2, signal lamps 30, 31 and 32 are provided whereby the tester may see at a glance in which circuit the trouble exists. If upon the insertion of plug 12' and 13' into jacks 10' and 9' respectively all the circuits are intact, the lamps 30, 31 and 32 will be illuminated and the buzzer 20' operated. The insertion of the plugs and the failure of any lamp to light would indicate trouble in the ring circuit including relay 14', since this relay controls the operation of all relays in the testing system. If lamp 30 is illuminated and lamps 31 and 32 are not lighted, key 21' is depressed and if lamp 31 thereupon fails to light, the tester knows that the sleeve circuit is open. The depression of key 22' completes the tip circuit and the illumination of lamp 32 and the operation of the buzzer 20' indicates the electrical continuity of this circuit.

What is claimed is:

1. In a testing system, a telephone line 65 comprising a plurality of conductors termi-

nating in as many terminals at a plurality of points, a plurality of electromagnetic devices, means for associating each of said devices with a different one of the terminals of said line at several points, a signaling device associated with one of said electromagnetic devices, the means for associating the electromagnetic devices with the telephone line being arranged so that the successive operation of said devices effects the 75 operation of the signaling device.

2. In a testing system, a jack having tip ring and sleeve terminals, a second jack having similar terminals, wires connecting like terminals of said jacks, a plug for each 80 of said jacks having corresponding tip ring and sleeve terminals, a signaling device associated with the tip terminals of said plugs, and means associated with the tip, ring and sleeve terminals of said plugs and 85 responsive to the association of said plugs with said jacks for effecting the operation of said signaling device, if a standard condition prevails at the tip, ring and sleeve terminals of said jack and the corresponding 90 wires.

3. In a testing system a plurality of multiple jacks and associated tip, ring and sleeve circuits, plugs and corresponding tip, ring and sleeve circuits for interconnecting 95 said jacks, means actuated by all of said plug circuits for indicating a standard condition of all of the jack circuits, and means associated with each of said plug circuits for detecting the presence of an unstandard 100 condition in the corresponding jack circuits.

4. In a testing system, a plurality of multiple jacks, a source of current for each of the type of contacts of said jacks, plugs 105 for interconnecting said jacks and associating each of said current sources with their respective type of jack contacts, tie wires connecting the contacts of each type in said jacks separately, an electromagnetic device for each of said type of contacts, a signaling device responsive to the association of said plugs with said jacks, the response thereof depending upon a standard condition of each of said tie wires and their corresponding jack contacts and a subsequent 110 successive operation of said electromagnetic devices, and manually operable means for effecting the operation of said signaling device should a break occur in any of said tie 115 wires or between any of said tie wires and its associated jack contacts.

5. In a testing system, a plurality of multiple jacks, plugs for interconnecting said jacks, a signaling device for each type of contacts of said jacks, means for successively operating said devices upon insertion of said plugs into said jacks, the actuation of said means depending upon the standard condition of said multiple jacks, and manually operable means for effecting 125 130

the operation of the remaining signaling devices should said first mentioned means fail to operate due to the failure of operation of one of said devices upon insertion of said 5 plugs into said jacks.

6. In combination, a plurality of jacks, multiple wires connecting the terminals of said jacks, and a testing device comprising a train of relays, a pair of plugs for connecting the relays to the jacks, and means 10 for indicating the standard condition of the jacks and multiple wires.

7. In a testing system a plurality of circuits to be tested, a train of relays, a circuit 15 for each of said relays so arranged that the operation of one relay closes the circuit for a succeeding relay in said train, a plurality of manual connecting terminals for connect-

ing the circuit for each relay independently to a corresponding circuit to be tested, and a 20 device controlled by the successive operation of said relays to give a signal if the circuits to be tested are all in a standard condition.

8. In combination, a plurality of jacks, multiple wires connecting like terminals of 25 said jacks, a device for testing the multiple connections between any two of said jacks comprising a train of relays operating automatically in response to the connection of the device to two of said jacks, and means 30 controlled by said relays for indicating the standard condition of said multiple wires.

In witness whereof, I hereunto subscribe my name this 14th day of June A. D., 1923.

FREDERICK J. MARTIN.
